UNITED STATES PATENT OFFICE.

BERT CREBBIN, OF BRIDGEPORT, ALABAMA, ASSIGNOR, BY MESNE ASSIGNMENTS, TO SARANAC MACHINE COMPANY, OF ST. JOSEPH, MICHIGAN, A CORPORATION OF MICHIGAN.

BOX-MAKING MACHINE.

1,123,250.

Specification of Letters Patent.

Patented Jan. 5, 1915.

Application filed April 1, 1905. Serial No. 253,291.

To all whom it may concern:

Be it known that I, BERT CREBBIN, a citizen of the United States, residing at Bridgeport, in the county of Jackson and State of Alabama, have invented a new and useful Box-Making Machine, of which the following is a specification.

This invention relates to box making machines, and particularly to machines for the manufacture of the side members of crates or boxes, the apparatus being so constructed that the strips of material or body members and battens necessary for the formation of the article will be automatically removed from suitable reservoirs or hoppers and properly assembled and presented to a stapling or wire stitching mechanism, the latter operating to secure the members together to form the finished article.

A further object of the invention is to provide improved means for insuring the placing of the strips in proper position with respect to each other to form articles of uniform character, and a still further object is to provide a machine in which the operation of the parts will be automatic throughout, it being merely necessary to keep the reservoirs or hoppers supplied with body members and battens of the proper size and shape.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit, or sacrificing any of the advantages of the invention.

In the accompanying drawings:—Figure 1 is a vertical sectional view of a box making machine construction in accordance with the invention. Fig. 2 is a plan view of the same, partly in section. Fig. 3 is an end elevation of the machine partly in section. Fig. 4 is a sectional elevation of the machine on an enlarged scale, on the line 4—4 of Fig. 1. Fig. 5 is a detail perspective view of a portion of one of the strip feeding devices. Fig. 6 is a perspective view of one of the crate sides united.

Similar numerals of reference are em-

ployed to indicate corresponding parts throughout the several figures of the drawings.

The working parts of the apparatus are supported on a suitable frame that is provided with bearings for the reception of a main driving shaft 11, from which motion is imparted to the strip carrying and stapling mechanisms.

The frame supports a horizontally disposed bed or table 12 having a plurality of longitudinally disposed parallel grooves 13, 14, 15, 16 and 17, in which are arranged traveling devices or link belts 18, 19, 20, 21, and 22, respectively, these belts serving as means for carrying the several body members and battens from their containing reservoirs or hoppers to the stapling or other securing means, and for delivering the finished article from the machine.

The two chains 19 and 21 pass over sprocket wheels secured to shafts 23 and 23^a arranged, respectively, in bearings at the opposite ends of the machine, and to the shaft 23 is secured a ratchet wheel 24 with which engages a spring pressed pawl 25 carried by an arm 26 that is fulcrumed on the shaft. One end of the arm 26 is connected by a rod 27 to the strap of an eccentric 28 that is secured to the main shaft 11, and at each rotation of the latter, the ratchet wheel is turned to the extent of one, two, or more teeth, in accordance with the feed desired. These chains are provided with upwardly projecting teeth or lugs 30, spaced at equidistant intervals and serving to engage and carry the longitudinal strips α along the bed or table 12.

At a point near the shaft 23^a, the frame is provided with supports for a reservoir or hopper 34 extending transversely of the machine and formed of sheet metal or structural iron. This reservoir or hopper receives the strips α which in practice form the body members or longitudinal strips of the crate side, as shown in Fig. 6, the strips being placed one on top of the other, and the lowermost strip resting on the bed or table, so that at each intermittent forward movement of the chains, one set of teeth 30 will engage with and remove the lowermost strip, allowing the next strip to fall against the table to be in turn moved along the table by the following set of teeth. The operation of this portion of the mechanism will

be apparent on reference to Fig. 1, where-in the teeth 30 are shown as engaging and carrying a plurality of strips arranged at equi-distant intervals.

5 The link belts 18, 20 and 22 pass over sprocket wheels, one set of which is secured to the shaft 23, and the opposite set to a shaft 36 that is disposed to the rear of a plurality of reservoirs 37, all of the same 10 construction and supported by suitable transverse bars 38 carried by the frame of the machine. These reservoirs or hoppers, three in number in the present instance, serve to receive the transverse strips or battens *y*, shown in Fig. 6, and the reservoirs 15 are of substantially the same construction as the reservoir 34. The strips or battens *y* placed in the reservoirs 37 are piled one on top of the other, and the lowermost strip 20 of each reservoir rests on the previously fed longitudinal strips *x* that are carried by the teeth 30, as will be apparent on reference to Fig. 1. The link belts 18, 20 and 22 are provided with teeth 39 arranged at 25 regular intervals, and these teeth are extended laterally from the belts and serve to engage the lowermost strips of the reservoirs 37 and feed the same uniformly with the transverse strips *x* toward the stapling 30 end of the machine, so that when presented at the latter point, the strips *x* will be supported by the table and the transverse strips *y* will rest upon the strips *x*.

The side members of the frame at the 35 front of the machine are provided with vertical guiding slots for the reception of the projecting ends of a vertically movable bar 40, and said projecting ends are provided with trunnions or studs 41 to which are connected the upper ends of operating rods 42, the lower end of each rod being connected to a strap carried by an eccentric 43 that is mounted on the main shaft 11. The bar 40 carries suitable staple drivers 44 which pass 45 through guides formed in the rigid frame, these staple drivers being of any ordinary construction.

In order to upset or clench the ends of the staples, anvils 45 in the form of adjusting studs are arranged on a vertically movable cross bar 46 that is carried by a pair of vertically disposed rods 47 arranged within the side frames of the machine, the lower ends of said rods being provided with 50 pins or anti-friction rollers 48 that are engaged by cams 49 mounted on the main driving shaft 11, the movement of the cams being so timed that after a staple has been forced through the strips, the anvils will be 55 moved quickly upward, striking hammer like blows which will bend the ends of the staples and force them into the wood.

In the operation of the machine, the chains are fed intermittently, and the strips 60 *x* are disposed at equi-distant intervals con-

tinuously throughout the length of the machine. The length of the strips *y* is such that they will extend over a number of the strips *x*, three in the present instance, or the number may be increased or diminished in 70 accordance with the character of the article being made, four being used in the article shown in Fig. 6 of the drawings.

For the broader purposes of my invention, I do not limit myself to any particular 75 use for the different features and combinations thereof, inasmuch as it is obvious that the same can be used for the production of various kinds of box or crate blanks. As shown and described, there are a plurality 80 of sets of feed chains, and on these chains there are means for engaging the edges of the sheet material, as well as means for engaging rear ends of certain of the materials. The portions which engage the edges of the 85 sheet material are in one plane, and the portions which engage rear ends of certain of the materials are in a different plane, but the two planes are parallel, and are preferably horizontal, although the exact position 90 of the machine is immaterial, so far as the broader aspects of my invention are concerned. As the sets of feed chains are of different lengths, it follows that in a machine embodying the principles of my invention one set of feed chains has movement 95 relative to another set of chains, but they move in unison where the blank is passing under the staplers. Also, and while these feed chains are carrying the sheet material 100 forward, parallel binding members, for example the strips *y*, are automatically fed on to the sheet material, in exact alignment with the staplers, whereby the different sections of sheet material are connected together to form a single blank. Again, and with the illustrative construction shown and described, the machine has both inner and outer lateral engagement with certain of the materials which travel endwise during the 110 operation of the machine, and it is by reason of this lateral engagement that the materials so engaged are caused to have proper 115 relative positions when the blank is finished. As shown, the hoppers provide this inner and outer lateral engagement with the side edges of the members *y* of the blank, thereby determining the distance between these materials of the blank; but I do not limit myself to any particular means for accomplishing 120 this positioning or spacing of the materials, nor to any particular time for so doing, the only requisite being that some provision be made for insuring the endwise travel of certain parts of the blank along 125 parallel paths extending directly in line with and below the stapler heads. Therefore, and as explained, and in addition to the engagement of certain portions of the link belt feed mechanism with the edges of 130

the sheet material, and the engagement of certain other portions with rear ends of certain elements of each blank, there is a further provision of means for automatically feeding parallel binding members on to the forward traveling sheet material, as well as the provision for effecting lateral engagement with some of the materials at a suitable time during the operation, whereby the materials are secured together in properly spaced relation.

Having thus described the invention, what is claimed is:—

1. In a machine of the class described, the combination with a plurality of reservoirs, of intermittently operable feeding mechanisms for removing strips of material from the reservoirs, comprising as many link-belts as there are cross strips, and a securing mechanism to which said strips are presented in properly spaced and crossed relation.

2. In a machine of the class described, the combination with a frame, of a table, a transversely extending strip-containing reservoir having an open bottom, endless belts having teeth for engaging the successively lowermost strips and moving the same in spaced relation on the table, a plurality of longitudinally disposed reservoirs carried by the frame and having their lower ends open to permit the feeding of strips on top of the previously fed transverse strips, feeding chains for engaging said longitudinally disposed strips, and a securing means to which the strips are presented at the completion of each feeding movement.

3. An assembler for automatically assembling the members of a side or top of a package, comprising spaced hoppers, one for containing the body members of the package and the other for containing the battens, and traveling devices, carried on as many link-belts as there are battens, passing underneath the hoppers for removing successively the members from the hoppers for superimposing the battens on the body members.

4. In a machine of the class described, the combination with an intermittently operable feeding means comprising a plurality of separate or structurally distinct and endless link belts, of different lengths, of a plurality of strip-containing reservoirs, of which one is disposed at a right angle to the others, devices on each of said belts for removing strips from the reservoirs, and maintaining the same in properly spaced relation, and an intermittently operable securing mechanism movable at the completion of each step of the feeding operation.

5. In a machine of the class described, the combination with step by step traveling feeding devices, comprising a plurality of separate or structurally distinct and endless

link belts, of different lengths, of strip containing reservoirs from which strips are fed in crossed and spaced relation, the shorter of said link belts being used for feeding the shorter of said strips, and means operable at the completion of each feeding movement to actuate said stapling mechanism for forcing securing staples through the strips.

6. The improved crate-side machine, provided with a plurality of slat-delivering hoppers spaced apart and positioned to feed a plurality of parallel strips cross-wise of a plurality of parallel members, and a plurality of separate and unconnected link belts, of different lengths, for removing the strips and members from the said hoppers, substantially as and for the purpose set forth.

7. In a machine of the class specified, the combination of a traveling work-holder, hoppers for the cross slats of a crate-side, means on the work-holder for spacing apart the long slats upon which the said cross slats are laid, means on the work-holder for engaging and removing the cross-slats from the hoppers, and means for intermittently advancing said work holder to intermittently feed the slats from said hoppers, said work-holder comprising as many link-belts as there are cross slats.

8. In a machine of the class described, adapted for making crate sides, the combination of a work-supporting structure comprising more than two parallel endless traveling link-belts, of different lengths, provided with means for holding a plurality of parallel slats with a plurality of parallel cross slats superimposed thereon, hoppers for containing and feeding the cross slats of each crate side, and means for producing relative traveling movement between the said work holding structure and the said hoppers, to produce the said automatic feeding of slats for each crate side, said work-holding structure being provided with means for engaging the ends of the cross slats and causing a proper discharge thereof from said hoppers.

9. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of sets of parallel link belts, the members of each set operating in unison, and the different sets each having positioning portions for engaging only certain elements of the blank, ratchet devices for causing all of said sets of link belts to have a step by step forward feeding motion in

- unison, to feed the blank materials to said staplers, and means for operating said staplers and ratchet devices, some of said portions engaging edges of the sheets, thereby spacing the sheets apart, and other said portions engaging ends of said materials, said edge engaging portions being all in one plane, and said end engaging portions being all in a different plane.
10. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of sets of parallel link belts, the members of each set operating in unison, and the different sets each having positioning portions for engaging only certain elements of the blanks, ratchet devices for causing all of said sets of link belts to have a step by step forward feeding motion in unison, to feed the blank materials to said staplers, means for operating said staplers and ratchet devices, some of said portions engaging edges of the sheets, thereby spacing the sheets apart, and other said portions engaging ends of said materials, said edge engaging portions being all in one plane, and said end engaging portions being all in a different plane, said link belts being disposed out of line with said staplers, and stationary means for supporting the blank materials during the stapling operation.
11. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of sets of parallel link belts, the members of each set operating in unison, and the different sets each having positioning portions for engaging only certain elements of the blank, ratchet devices for causing all of said sets of link belts to have a step by step forward feeding motion in unison, to feed the blank materials to said staplers, and means for operating said staplers and ratchet devices, some of said portions engaging edges of the sheets, thereby spacing the sheets apart, and other said portions engaging ends of said materials, said edge engaging portions being all in one plane, said end engaging portions being all in a different plane, said link belts being all

disposed in another plane, and said planes being all parallel and one above the other.

12. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of separate and parallel link belts, each having portions for engaging edges of said sheets in one plane and other portions for engaging ends of said materials in a different plane, all said portions secured directly to said link belts, said planes being parallel, ratchet devices for causing said belts to have a step by step forward feeding motion in unison, to feed the blank materials to said staplers, and means for operating said staplers and ratchet devices.

13. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of separate and parallel link belts, each having portions for engaging edges of said sheets in one plane and other portions for engaging ends of said materials in a different plane, all said portions secured directly to said link belts, said planes being parallel, ratchet devices for causing said belts to have a step by step forward feeding motion in unison, to feed the blank materials to said staplers, and means for operating said staplers and ratchet devices, said link belts being disposed out of line with said staplers, and stationary means for supporting the blank materials during the stapling operation.

14. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of separate and parallel link belts, each having portions for engaging edges of said sheets in one plane and other portions for engaging ends of said materials in a different plane, all said portions secured directly to said link belts, said planes being

parallel, ratchet devices for causing said belts to have a step by step forward feeding motion in unison, to feed the blank materials to said staplers, and means for operating said staplers and ratchet devices, said link belts being all disposed in another plane, and the three planes being one above the other.

15. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including positioning portions for engaging edges of said sheets and positioning portions for engaging ends of said materials, said edge engaging portions being in one plane, and said end engaging portions being in a different plane, the two planes being parallel, ratchet devices, means coöperating therewith to cause the said portions and materials to have an intermittent motion, thereby to feed the materials to said staplers, means whereby the said portions of one kind reverse their movement and begin to move forward at a greater distance from the staplers than the other kind, and means for operating said staplers and ratchet devices.

16. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including positioning portions for engaging edges of said sheets and positioning portions for engaging ends of said materials, said edge engaging portions being in one plane, and said end engaging portions being in a different plane, the two planes being parallel, ratchet devices, means coöperating therewith to cause the said portions and materials to have an intermittent motion, thereby to feed the materials to said staplers, and means for operating said staplers and ratchet devices, said planes being disposed one above the other, and the edge engaging portions having movement relative to and different from that of said end engaging portions.

17. A box or crate blank machine comprising a gang of staplers, instrumentalities for successively presenting to said staplers a plurality of separate sheets included with other materials in a single blank, and for

spacing said sheets apart, means for supplying parallel binding members upon said sheets, to be secured thereto by said staplers, for connecting the sheets together in spaced relation, said instrumentalities including positioning portions for engaging edges of said sheets and positioning portions for engaging ends of said materials, said edge engaging portions being in one plane, and said end engaging portions being in a different plane, the two planes being parallel, ratchet devices, means coöperating therewith to cause the said portions and materials to have an intermittent motion, thereby to feed the materials to said staplers, and means for operating said staplers and ratchet devices, said edge engaging portions being structurally distinct from said end engaging portions, being separately supported independently thereof, and having movements relative thereto.

18. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of sets of parallel link belts, the members of each set operating in unison, and the different sets each having positioning portions for engaging only certain elements of the blank, ratchet devices for causing all of said sets of link belts to have a step by step forward feeding motion in unison, to feed the blank materials to said staplers, and means for operating said staplers and ratchet devices, some of said portions engaging edges of the sheets, thereby spacing the sheets apart, and other said portions engaging ends of said materials, said edge engaging portions being all in one plane, and said end engaging portions being all in a different plane, said means for supplying the binding members being subject to the intermittent action of said ratchet devices, and having guiding provisions for feeding said members on to the sheets in exact alinement with the staplers.

19. A box or crate blank machine comprising a gang of staplers, instrumentalities for successively presenting to said staplers a plurality of separate sheets included with other materials in a single blank, and for spacing said sheets apart, means for supplying parallel binding members upon said sheets, to be secured thereto by said staplers, for connecting the sheets together in spaced relation, said instrumentalities including a plurality of separate and parallel link belts, each having portions

for engaging edges of said sheets in one plane and other portions for engaging ends of said materials in a different plane, all said portions secured directly to said link
5 belts, said planes being parallel, ratchet devices for causing said belts to have a step by step forward feeding motion in unison, to feed the blank materials to said staplers, and means for operating said staplers and
10 ratchet devices, said means for supplying the binding members being subject to the intermittent action of said ratchet devices, and having guiding provisions for feeding said members on to the sheets in exact alignment with the staplers.

20. A box or crate blank machine comprising a gang of staplers, instrumentalities for successively presenting to said staplers a plurality of separate sheets included with
20 other materials in a single blank, and for spacing said sheets apart, means for supplying parallel binding members upon said sheets, to be secured thereto by said staplers, for connecting the sheets together in spaced
25 relation, said instrumentalities including positioning portions for engaging edges of said sheets and positioning portions for engaging ends of said materials, said edge engaging portions being in one plane, and said
30 end engaging portions being in a different plane, the two planes being parallel, ratchet devices, means coöperating therewith to cause the said portions and materials to have an intermittent motion, thereby to feed the materials to said staplers, means whereby the said portions of one kind reverse their movement and begin to move forward at a greater distance from the staplers than the other kind, and means for operating said
35 staplers and ratchet devices, said means for supplying the binding members being subject to the intermittent action of said ratchet devices, and having guiding provisions for feeding said members on to the sheets in
40 exact alignment with the staplers.

21. A box or crate blank machine comprising a gang of staplers, instrumentalities for successively presenting to said staplers a plurality of separate sheets included with
50 other materials in a single blank, and for spacing said sheets apart, means for supplying parallel binding members upon said sheets, to be secured thereto by said staplers, for connecting the sheets together in spaced
55 relation, said instrumentalities including a plurality of sets of parallel link belts, the members of each set operating in unison, and the different sets each having positioning portions for engaging only certain elements of the blank, ratchet devices for causing all of said sets of link belts to have a step by step forward feeding motion in unison, to feed the blank materials to said
60 staplers, and means for operating said

staplers and ratchet devices, some of said 65 portions engaging edges of the sheets, thereby spacing the sheets apart, and other said portions engaging ends of said materials, said edge engaging portions being all in one plane, and said end engaging portions 70 being all in a different plane, the said machine having inner and outer lateral engagement with some of said materials to insure exact alinement of said ends in parallel paths of travel which are in line with 75 said staplers.

22. A box or crate blank machine comprising a gang of staplers, instrumentalities for successively presenting to said staplers a plurality of separate sheets included with 80 other materials in a single blank, and for spacing said sheets apart, means for supplying parallel binding members upon said sheets, to be secured thereto by said staplers, for connecting the sheets together in spaced 85 relation, said instrumentalities including a plurality of separate and parallel link belts, each having portions for engaging edges of said sheets in one plane and other portions for engaging ends of said materials in a 90 different plane, all said portions secured directly to said link belts, said planes being parallel, ratchet devices for causing said belts to have a step by step forward feeding motion in unison, to feed the blank materials to said staplers, and means for operating said staplers and ratchet devices, the said machine having inner and outer lateral engagement with some of said materials to insure exact alinement of said ends in paths 95 of travel which are in line with said staplers.

23. A box or crate blank machine comprising a gang of staplers, instrumentalities for successively presenting to said staplers 105 a plurality of separate sheets included with other materials in a single blank, and for spacing said sheets apart, means for supplying parallel binding members upon said sheets, to be secured thereto by said staplers, 110 for connecting the sheets together in spaced relation, said instrumentalities including positioning portions for engaging edges of said sheets and positioning portions for engaging ends of said materials, said edge engaging portions being in one plane, and said end engaging portions being in a different plane, the two planes being parallel, ratchet devices, means coöperating therewith to cause the said portions and materials to 115 have an intermittent motion, thereby to feed the materials to said staplers, means whereby the said portions of one kind reverse their movement and begin to move forward at a greater distance from the staplers than the other kind, and means for operating 120 said staplers and ratchet devices, the said machine having inner and outer lateral en-

gagement with some of said materials to insure exact alinement of said ends in paths of travel which are in line with said staplers.

- 5 24. A box or crate blank machine comprising a gang of staplers, instrumentalities for successively presenting to said staplers a plurality of separate sheets included with other materials in a single blank, and for 10 spacing said sheets apart, means for supplying parallel binding members upon said sheets, to be secured thereto by said staplers, for connecting the sheets together in spaced relation, said instrumentalities including a 15 plurality of sets of parallel link belts, the members of each set operating in unison, and the different sets each having positioning portions for engaging only certain elements of the blank, ratchet devices for causing 20 all of said sets of link belts to have a step by step forward feeding motion in unison, to feed the blank materials to said staplers, means for operating said staplers and ratchet devices, some of said portions 25 engaging edges of the sheets, thereby spacing the sheets apart, and other said portions engaging ends of said materials, said edge engaging portions being all in one plane, and said end engaging portions being all in 30 a different plane, and means from which said sheets are successively and automatically fed into advancing position by said edge engaging portions, coöperating with said member supplying means to assemble 35 the materials in properly spaced and crossed relation, with said ends in proper relation to the sheet edges.
25. A box or crate blank machine comprising a gang of staplers, instrumentalities 40 for successively presenting to said staplers a plurality of separate sheets included with other materials in a single blank, and for spacing said sheets apart, means for supplying parallel binding members upon said 45 sheets, to be secured thereto by said staplers, for connecting the sheets together in spaced relation, said instrumentalities including a plurality of separate and parallel link belts, each having portions for engaging edges of 50 said sheets in one plane and other portions for engaging ends of said materials in a different plane, all said portions secured di-
- rectly to said link belts, said planes being parallel, ratchet devices for causing said belts to have a step by step forward feeding motion in unison, to feed the blank materials to said staplers, means for operating said staplers and ratchet devices, and means from which said sheets are successively and automatically fed into advancing position by said edge engaging portions, coöperating with said member supplying means to assemble the materials in properly spaced and crossed relation, with said ends in proper relation to the sheet edges. 5
26. A box or crate blank machine comprising a gang of staplers, instrumentalities for successively presenting to said staplers a plurality of separate sheets included with other materials in a single blank, and for 70 spacing said sheets apart, means for supplying parallel binding members upon said sheets, to be secured thereto by said staplers, for connecting the sheets together in spaced relation, said instrumentalities including 75 positioning portions for engaging edges of said sheets and positioning portions for engaging ends of said materials, said edge engaging portions being in one plane, and said end engaging portions being in a different 80 plane, the two planes being parallel, ratchet devices, means coöperating therewith to cause the said portions and materials to have an intermittent motion, thereby to feed the materials to said staplers, means whereby the said portions of one kind reverse their movement and begin to move forward at a greater distance from the staplers than the other kind, means for operating said 85 staplers and ratchet devices, and means from which said sheets are successively and automatically fed into advancing position by said edge engaging portions, coöperating with said member supplying means to assemble the materials in properly spaced and 90 crossed relation, with said ends in proper relation to the sheet edges.
- In testimony that I claim the foregoing as my own, I have hereto affixed my signature in the presence of two witnesses.
